UNITED STATES PATENT OFFICE.

WILLIAM S. GIEBS, OF INDIANAPOLIS, INDIANA.

TELEPHONE RECEIVER STAND.

Application filed November 26, 1919. Serial No. 340,834.

To all whom it may concern:

Be it known that I, WILLIAM S. GIEBS, a citizen of the United States, residing at Indianapolis, in the county of Marion and

5 State of Indiana, have invented certain new and useful Improvements in a Telephone-Receiver Stand, of which the following is a specification.

My invention relates to improvements in 10 stands for telephone receivers and has for its primary object to provide a device of this character that will independently support the receiver in a convenient position, leaving the hands of the user free to take 15 notes of the telephone conversation necessary.

A further object of the invention lies in the provision of a device of this character capable of being adjusted vertically, 20 permitting the receiver to be positioned at any desired height, so as to be unlimited in its application.

A further object of the invention lies in the provision of a device of this character 25 that is simple and neat in construction, reliable and efficient in use, and inexpensive to manufacture.

Other objects and advantages of the invention will be apparent during the course 30 of the following description.

In the accompanying drawings forming a part of this specification and in which like numerals are employed to designate like parts throughout the same,

35 Figure 1 is a fragmentary perspective view of the invention, and

Figure 2 is a top or plan view of the stand used in connection with my invention.

In the drawings, wherein for the purpose 40 of illustration I have shown a preferred embodiment of my invention, the numeral 5 designates the casing of the base which is square in configuration having its sides beveled as at 6, and preferably constructed

45 of enameled tin or other suitable material. The base is filled with concrete 7 or other heavy substance which holds the base in a substantially stationary position. To prevent the base from scratching when moved 50 across the surface of the table on which it is positioned, the bottom is covered with a layer of felt 8 or other padding.

Extending upwardly from the center of the base is a hollow pedestal 9 constructed 55 of two telescoping tubes 10 and 11 which are held in their adjusted position through

the medium of the set screw 12 which passes through the tube 10. The construction heretofore disclosed constitutes the base or pedestal which regulates the height 60 at which the receiver is positioned.

The support which forms a seat for the receiver is formed from a single strand of wire 13 which is curved intermediate its length, having its ends extending in diverging relation to each other forming side arms and twisted adjacent their terminals as at 14. The twisted portion 14 is bent as at 14', so as to extend beneath the side arms and in parallel relation therewith. At 70 a point approximately midway the length of the side arms, the twisted portion is bent at right angles, as at 15, to provide a stem which extends downwardly into the tube 11. A set screw 16 regulates the adjustment of the support, also holding it in a stationary position. The forward end or curved portion of the support is bent downwardly at right angles, as at 16', forming a substantial U shaped yoke 17 which receives 80 and supports the enlarged end of the receiver 18. The side arms of the frame are inclined slightly rearwardly so as to avoid accidental displacement of the receiver.

In use, the stand is adapted for use in 85 connection with telephones and may be placed or positioned near the stand upon which the phone is supported. When using the phone, the user may adjust the pedestal to the desired height and by placing the receiver in the frame support, his hands will be free to take notes of the telephone conversation if so desired. This device is also useful for persons who are minus their hands and will permit them to use the phone 90 as conveniently as parties having both hands. Particular attention is called to the simple and efficient manner in which the support is constructed permitting the manufacture at a minimum cost.

100 It is to be understood that the form of my invention herewith shown and described is to be taken as a preferred example of the same, and that certain changes in the shape, size, and arrangement of parts may be resorted to without departing from the spirit of the invention or the scope of the subjoined claim.

Having thus fully described my invention, I claim:

110 In a telephone receiver stand, the combination with a weighted base having an

adjustable pedestal, of a receiver support comprising a strand of wire bent intermediate its length to provide spaced diverging arms forming a body portion, the forward 5 end of the body portion being bent downwardly to provide a U-shaped yoke for the large end of the receiver, and the free ends of said arms being folded upon themselves and twisted together to form a single arm 10 extending on a horizontal plane beneath the

body in spaced relation thereto, said arm being bent downwardly at right angles midway the length of the body to provide a stem for mounting in the pedestal.

In testimony whereof, I have affixed my 15 signature in the presence of two witnesses.

WILLIAM S. GIBBS.

Witnesses:

FRANK A. JORDAN,

MARY CATHERINE BURK.
